UNITED STATES PATENT OFFICE.

JOHN THOMSON, OF BROOKLYN, NEW YORK, ASSIGNOR TO MARIA T. BARTON, OF SAME PLACE.

DIAPHRAGM-METER.

SPECIFICATION forming part of Letters Patent No. 274,848, dated March 27, 1883.

Application filed August 28, 1882. (No model.)

To all whom it may concern:

Be it known that I, JOHN THOMSON, a citizen of the United States, residing at Brooklyn, county of Kings, and State of New York, 5 have invented new and useful Improvements in Fluid-Meters, of which the following is a specification.

My invention has for its object to produce a piston-meter that shall be practically frictionless in its action, and will not require that the piston shall be packed nor the cylinder finished on its inner face. It is also my purpose to supply a meter in which the inflow and the outflow shall be controlled by a system of 10 pup-
pet-valves, requiring the minimum of parts and of labor for their construction and the minimum of power to effect their operation with certainty of operation under all circumstances.

20 To this end my invention consists in a piston-meter having a cylindrical shell, within which is arranged a filling and collapsing lining, both piston and lining operating freely without contact on the sides of the cylinder.

25 My invention also consists in a spring valve-action combined with a positive valve-action, the arrangement being such that the motor-springs shall also act as retaining-springs until the instant that a reversal of the valve 30 movement is required, while the positive action shall not be operative, except in the event of a failure upon the part of the motor-springs to actuate the valves.

35 My invention also consists in an improved construction of the valves and the valve-seats, the former being provided with a yielding annulus set in and projecting slightly from the face of the valve, while the latter is formed with V-shaped annular grooves formed in the 40 face upon which the valve seats, whereby a series of separate contact-surfaces is formed, while at the same time not only is the metallic clinking of the valve prevented, but as the latter do not need to be finely fitted, they can 45 be much more cheaply produced.

Referring to the drawings, Figure 1 is an elevation. Fig. 2 is a central vertical section of Fig. 1. Fig. 2^a is a central vertical section of the inner lining of the cylinder detached. 50 Fig. 2^b is a detail view of part of the valve-

operating mechanism detached. Fig. 2^c is a view of a modified form of the parts shown in Fig. 2^b. Fig. 3 is a plan view, showing the valve-actuating mechanism and the waterways, the cylinder being inverted so that said view is taken from below. Fig. 4 is an end view of part of the valve-actuating mechanism detached. Fig. 5 is a diagram showing the mode of operation of the motor-valve springs. Fig. 6 is a view showing a modified form of 55 spring. Fig. 7 is a view of the motor-spring bearing with its journals. Fig. 8 is a plan view of the cylinder-cap inverted. Fig. 9 is a section on line 1 1, Fig. 8, showing the valves in reverse position from that in Fig. 1. Fig. 10 is a central vertical section of one of the valves, the parts being enlarged. Fig. 11 is a central vertical section of one of the valves, the parts being enlarged.

The ordinary construction and operation of 70 piston-meters require no explanation, save that the three dominant points most desirable of accomplishment in their construction are, first, cheapness; second, accuracy, and, third, the least possible friction in operation. Should 75 the contact of the piston and the cylinder be imperfect, the measurement of volume will be correspondingly inaccurate. If the fitting between the piston and the cylinder be perfect, sufficient friction will be engendered to require 80 a considerable degree of energy from the flowing current, and the volume of egress is thus diminished in direct ratio to the duty performed. The theoretically-perfect fluid-meter is one which measures volume regardless of 85 the head or pressure upon the inflowing stream, and which therefore requires no energy from the passing current to effect the measurement.

In order that the piston may operate, it is necessary that the current shall be alternately 90 from each face of the piston, and to accomplish this a system of valves is required with mechanism for operating them. In order that these valves may do their duty in the best possible manner, it is required that they shall 95 practically make an instantaneous change of position with the least possible expenditure of power. To this end the parts should be as easily operated, as simple, and as few as possible.

In carrying out my invention I first provide a cylinder having a cap, 8, which fits upon said cylinder and is bolted or otherwise attached thereto. Within this cylinder, which requires no finishing upon its inner face, is placed a flexible lining, 3, preferably formed like a bellows, and having its upper edge, 4, laid between the said cylinder and its cap, whereby the same forms a lining or packing between the two, as shown in Fig. 2. To the bottom of said lining is attached a ring, or, as it may be, a disk, 2, which connects directly with a piston-rod, 5, which is centrally secured in the cap 8, and which is provided with two caps or collars, 6 and 51, the function of which will be hereinafter explained. The collar 6, which is the upper collar, moves freely in a vertical bearing, 7, formed in the cap of the cylinder, as shown in Fig. 2. The flexible lining 3 is provided with rings 9 and 10, the former being inner and the latter outer rings, the rings 9 preventing a collapse of the lining from external pressure, while the rings 10 prevent the outward rupture of the lining from internal pressure. The difference in pressure within the meter as between the ingress and egress current is the sum total of the friction upon the current in passing the sluices and valve-ports, and the motive energy required to fill and collapse the lining and to throw the valves. As in this instance the excess of pressure to be restrained by the lining is exceedingly slight, as will be hereinafter more fully shown, the rings 9 and 10 may be made of small light wire. The lining 3 is made of some flexible fluid-proof material, either rubber, rubber cloth, or any other textile material, and it may also be constructed in sections fastened together, or it may be woven as a whole.

It will readily be seen that as the piston-rod travels up and down, the rings 9 and 10, being rigid, cause the buckling of the lining to be divided equally between each fold, and hence the friction upon the material itself is reduced to the minimum, while at the same time the loss of space is greatly diminished.

The arrangement of the parts mentioned is shown in Fig. 2, the piston having nearly completed its downward stroke, its collar 6 being brought into contact with the end of the lever 11, which actuates the spring-carriage 12. (See also Figs. 2^b, 2^c, 3, and 4.) I have shown in the drawings only two valves, 13 and 14, both being on the same valve-stem, 15. To place the valves in position the bushing 16 is first forced tightly to the seat formed in the cap 8. Then the upper valve and valve-stem are inserted, and next the double bushing 17, which forms an accurate bearing for the valve-stem, this bushing being forced to a separate seat. Lastly, the lower valve is inserted and secured in place on the valve-stem, and the lower bushing, 19, is then forced into its seat. In this manner it is simply necessary that each bushing, valve, and seat, which are in the form of circular steps, as shown in Figs. 2, 9,

10, and 11, shall be of accurate measurement, respectively, in order to insure a perfect seating of the double valve actuated by the single stem.

In the position of the valves as shown in Fig. 2 the entering current passes through the cored opening 20, which connects with the lower valve-chamber, 21, and finds an outlet to the upper portion of the cylinder through the open port 23, thereby filling the lining 3 and forcing the piston down. Meantime the fluid in the lower compartment, 24, of the cylinder, and which has occupied the space now being filled by the flexible lining 3, is being forced up through the cored sluiceway 25 to the intermediate valve-chamber, 26, and from thence through the now open port 27 to the final egress-slue 28, and thence outward. When the valves are reversed and the movement of the piston changed the inflowing current passes back through the way 25, while the contents of the flexible lining is discharged through the way 45, Fig. 9, and thence out by the final outlet 28, as in the first instance. As herein shown and described, the two valves, both being mounted upon a single valve-stem and all contained and acting within a single but subdivided valve-chamber, properly form, and will be so termed, a "compound puppet-valve." Aside from the features already described as attendant upon this construction of valve and water-ways, there is a yet more important advantage, in that the valve is perfectly balanced within itself in either or both positions against excess of pressure from within the meter or back-pressure from without the meter, as, say, in the case of, "water-hammer." This function of the valve is owing to the following conditions, namely: First, all of the valve parts are of equal area; second, the pressure of the ingress-current, as the case may be, is equally divided upon both outside faces of the valve or upon both inside faces of the valve, the conditions being reciprocal; third, the pressure of the egress-current is likewise equally divided upon either the two outside or inside faces of the valve. The conditions being as stated, it is evident that the egress sides of the valve may be without pressure, or as zero, while the ingress sides may be as 100 above zero, without interfering in the slightest with the operation of the valve, in that the excess of pressure between the outer and inner chambers is resisted by the valve-stem or the valve itself as a whole, and not between the valve-faces and the valve-seats. Hence, as a necessary consequence, the valve with respect to the fluid or varying pressure within the meter is in a state of perfect equilibrium, its impact and pressure upon the valve-seats being an exact determinable quantity dependent entirely upon its motor apparatus.

The valve-stem 15, upon which the valves 13 and 14 are mounted, is actuated by springs 29 and 30, (see Figs. 3 and 4,) in the manner following: These springs, which are prefera-

bly V-shaped, are connected at their outer ends to a carriage, 12, each spring having its own separate connection, and being of equal tension to the other. Their inner ends are connected to the valve-stem 15 by a single connection, 32, which is accurately centered on said stem. The action of these springs is in the nature of elastic toggles, wherein, after the "dead-point" has been passed, they have a throw either upward or downward, according as their inward ends are above or below the outer points of connection, and by this means their operation is rendered instantaneous, or practically so. The carriage 12, to which the outer end of said springs are connected, is raised and lowered relatively to the valve-stem by means of an arm or lever, 34^b, which is pivoted to the cylinder-cap at 34, and has its forked ends connected to the ends of the carriage 12 by their forked extremities 34^c. The free end of this lever, which is shown at 11, Figs. 2 and 2^b, lies directly beneath the collar 6 of the piston 5, and said end is provided with studs 41, which moves in curved slots 42, said slots being formed in ears of an idle-lever, 39, lying directly below said lever 34^b, and having its end beyond the said ears connected pivotally with the cylinder-cap 8 by pivot-bearings 40. The springs 29 and 30 are connected at their outer ends with the carriage 12 by means of bearings 31, journaled in said carriage, so that they may turn freely, and thus allow the springs to exert their force of compression merely. It will now be seen that as the flexible lining 3 fills the piston-rod 5 will be drawn down, and that just before said lining is filled to its capacity the collar 6 will strike the end 11 of the lever 34^b, carrying said lever down with it, and thereby elevating the opposite end. Now, by reference to Fig. 5 it will be seen that after the carriage 12 is raised to such a point that the outer ends of the springs 29 and 30 have passed the "dead-point"—viz., the point where the outer and inner ends of said springs are in the same horizontal plane—the said springs, as their outer ends continue to rise, will begin to exert a tendency to throw the valve-stem downward, as shown in dotted lines in said Fig. 5. As said springs pass farther from the dead-point, which is indicated by the line 37, Fig. 5, this tendency will become stronger, until finally they will snap the valve-stem 15 downward, and thereby reverse the action of the valves 13 and 14.

It will be noticed that in Fig. 4 the carriage 12 is guided by standards 33^a, having stop-heads 33 and stop-collars 36, by which the movement of the carriage is limited. In case, however, the springs 29 and 30 fail to act, the idle-lever 39 will operate the valve-stem in the manner following.

As already described, the lever 34^b has, upon its free end 11, studs which run in slots 42 formed in ears upon the said idle-lever 39.

As these studs reach the end of said slots the piston-collar 6 bears directly upon said lever,

which, being a lever of the third order, draws the valve-stem downward, and thereby operates the valves without the agency of the springs 29 and 30. It should, however, be noticed that the moment the valve-stem is actuated by this idle-lever the springs are called into action and aid said operation and render it instantaneous.

It will be seen that I derive a great advantage from carrying the heels of these springs upward instead of having their centers carried downward; also, that, should the springs begin to act before the carriage strikes the upper stops, 36, they will merely throw said carriage against these stops, and then throw the valve-stem downward; but the great advantage of this form of construction is that, as will readily be seen, the springs, after they have snapped the valves against their seats, will hold them there until the inflation or collapse of the lining 3 shall again operate the lever 34^b by means of its upper or lower collar, 6 or 51, thereby holding the valves against their seats by the force of said springs until the meter again fills.

By reference to Fig. 3 it will be seen that the lever 34^b has its end constructed with an open loop, so that the collars 6 and 51 on the piston-rod may pass without actuating said lever, the latter being operated by means of the studs 41 thereon, which run in slots 42 in the ears upon lever 39, and which, by striking the upper or lower ends of said slots, operate the idle-lever. By this construction it is evident that a much lighter set of springs may be used than if it were first necessary to overcome the resistance of a separate retaining-spring or set of springs, and were also required to always unseat the valves when said springs were in their "dead-points." The advantage of this is increased durability of the parts and less power to operate. It will be noticed that the leverage is in favor of the piston, in time, while accumulating force in the springs through the carriage-lever 34^b, while in the case of the idle-lever 39 the leverage is against the piston in the operation of the valves, and to this end—namely, that as this positive operation of the valves in the manner described is exceptional—it is required that the reversal shall be effected in the least possible time, thereby but slightly affecting the proper duty of the meter.

In Fig. 2^a I have shown a modification of the idle-lever, the operation of which is so apparent that it requires no description.

Fig. 6 also shows a slight modification in the form of the springs, being a double V shape, with end coiled to form a connection for a pin or other bearing.

In constructing the valves 13 and 14 I cut an annular channel in each face thereof, and place therein any suitable slightly-yielding material, 47, which is forced into said channel with its grain toward the valve-seat, as shown in Fig. 10. In the valve-seat, also, I form a series of annular V-shaped channels or grooves,

as shown in Fig. 11, upon which the grain edge of the packing material 47 impinges, thereby forming a number of separate annular contacts, which gives a much more perfect result.

The meter may be connected with any suitable register by means of a rod, 50, Fig. 2, which is acted upon by the upper and lower piston-rod collars, 6 and 51, the upper part of the said rod being packed through the cap, and carrying a pawl, 52, which meshes with a ratchet-wheel, 53. The connections of the toggle-springs to the carriage and valve-stems are shown as formed of journal-bearings, which is thought to be preferable, as they present the greatest wearing-surface and yet operate with slight friction. It is evident, however, that the toggle-springs might be connected by semi-circular bearings or knife-edge contacts where shown as journaled without affecting the principle of operation.

The construction described renders this form of meter cheap and easily made, durable and efficient in operation, and of great accuracy.

What I claim is—

- 25 1. In a fluid-meter, the combination, with a piston-rod having stop-collars thereon, of a spring-carriage, springs mounted thereon, and a valve-stem connected with said springs, substantially as described.
2. In a fluid-meter, the combination, with a piston-rod having stop-collars thereon, of a carriage-actuating motor and retaining-springs, and a valve-stem, substantially as described.
- 35 3. In a fluid-meter, the combination, with a piston-rod having stop-collars thereon, of a spring-carriage, springs mounted thereon, a valve-stem connected with said springs, and an idle-lever having an independent connec-

tion with said valve-stem, substantially as described.

4. In a fluid-meter, the combination, with the valve-stem, of carriage-actuating V-shaped springs, which connect at one end with said carriage and at the other end with said valve-stem, the movable carriage, whereby the springs act both as motor and as retaining-springs, substantially as described.

5. In a fluid-meter, a valve having set in its face a plane-faced annulus of yielding material, and a valve-seat having V-shaped annular grooves formed therein, whereby when the valve is seated a number of separate annular contacts between the said two parts will be made, substantially as described.

6. The combination, with the piston-rod having an upper and a lower collar, of a register-rod packed through the cylinder-cap and actuated by the collars upon said piston-rod, substantially as described.

7. The combination, with the cylinder having the water-ways 20, 25, and 28, of the valves 13 and 14, spring-carriage actuated by the piston-rod 5, and the flexible lining 3, substantially as described.

8. In a fluid-meter, the bushings 16, 17, and 19, fitted within the cap 8 in the manner described, and the valve-stem passing through said bushings and carrying valves which work between the bushings, substantially as shown and specified.

In testimony whereof I have hereunto set my hand in the presence of two subscribing witnesses.

JOHN THOMSON.
